UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed July 2, 1921. Serial No. 482,011.

To all whom it may concern:

Be it known that I, RAY S. WILBUR, a citizen of the United States of America, residing at Lyndhurst, in the county of Bergen, State of New Jersey, have invented certain new and useful Improvements in Signaling Systems, of which the following is a full, clear, concise, and exact description.

10 This invention relates to repeating systems and more particularly it relates to composite four-wire repeater circuits.

One of the objects of this invention is to provide means for insuring the selective 15 amplification or repeating of the different types of signals employed in a signaling system.

In composite repeater systems wherein the sides of the telephone line are employed also for the transmission of the 20 telegraph impulses, there occur in the line three types of signals, the telephone signaling currents, the telegraph currents and the ringing currents. In such a system it is frequently desirable to avoid the passage and 25 consequent amplification of the telegraph currents through the telephone repeaters, since it has been found that the telegraph signals cause disturbances in and affect the transmitting qualities of the talking circuit 30 if they are so amplified. In accordance with this invention, the selective amplification of these signals of different types is accomplished, in the case where it is desired 35 to amplify the ringing currents by the telephone repeater while not impressing thereon the telegraph signals, by providing a wave filter in front of the repeater so designed so as to suppress all frequencies below the 40 range of importance in speech. The telegraph signals are transmitted around the filter and the repeater through a by-path containing choke coils for preventing speech currents from being transmitted there- 45 through. Such an arrangement, while securing the proper differentiation between the telegraph and the telephone currents, does not provide for the transmission of the ringing currents through or around the repeater. In case it is desired to amplify the 50 ringing currents by the same amplifier as the speech currents, this difficulty may be overcome by providing a suitable path around the filter, which path by means of an anti-resonant circuit will transmit therethrough

the ringing frequency currents, while suppressing the transmission of the telegraph currents.

This invention will be better understood by reference to the following detailed description taken in connection with the accompanying drawing, in which the figure is a diagrammatic representation of a portion of a four-wire repeating circuit showing this invention applied thereto.

The invention is shown in connection with one of the transmission lines of the repeater circuit, it being understood that the remaining portion of the circuit associated with the other transmission line is a duplicate of that shown in the drawing.

In the drawing 10, 11 represents an incoming line section of a four-wire repeater circuit, and 12, 13 represents an outgoing section thereof. Between these line sections are provided two vacuum tube repeaters 14 and 15 arranged, as will be hereinafter apparent, to amplify the ringing and the voice currents from line section 10, 11. These repeaters are of the well known discharge tube type and comprise filaments 16, 17, anodes 18, 19 and control electrodes 20 and 21. The circuit arrangement shown in connection with these amplifiers is of a type now well known in the art and a detailed description thereof is therefore not deemed necessary.

Located between the amplifier 14 and the incoming line section 10, 11, is a wave filter comprising series capacities 23 and shunt inductances 24. The elements of this wave filter should preferably have such pre-assigned values that the filter is of the so-called high pass type and suppresses all frequencies below the essential voice range, for example, it may suppress all frequencies below 200 cycles per second. The values these elements should have to accomplish this result, may be readily obtained by reference to the United States patent to Campbell on wave filters No. 1,227,113 of May 22, 1917. Speech currents from line section 10, 11 by transformers 26 and 27 will be freely transmitted through the wave filter and by the input transformers 28 and 29 will be impressed upon the input circuit of repeater 14 amplified thereby and after a second amplification by repeater 15 will be impressed upon the outgoing line section 12, 13. Element 25 is the usual gain adjusting poten-

tiometer for determining the amount of gain of repeaters 14 and 15. An attenuation equalizer for the telephone currents is shown as connected between the secondary windings of transformers 26 and 27 and comprising an inductance 46 and a capacity 47 shunted by a resistance 48.

In order to transmit the telegraph currents around the wave filter and the repeaters, a by-path 30 may be provided from line wire 10 to line wire 12 and a similar by-path 31 may be provided for transmitting the currents from line wire 11 to line wire 13. Each of the by-paths 30 and 31 is preferably connected to each line wire, as shown, by a connection to a shunt path across each line section comprising inductances 33 and 34 and condensers 35 and 36. Inductances 33 and 34 serve to prevent the speech currents from being short-circuited by this shunt path while condensers 35 and 36 aid in the prevention of the interference between the two grounded telegraph channels 10, 30, 12 and 11, 31, 13. Series condensers 39, 40, 41 and 42 may also be provided to prevent telegraph signals from one line wire from going through the associated transformer windings to the other line wire thereby producing interference. The by-paths 30 and 31 should preferably be provided with choke coils, such as 44 and 45 to prevent any of the speech currents from being by-passed around the repeater elements so that only currents of frequencies of the order of 12 cycles or less are efficiently transmitted therethrough.

Since the wave filter disclosed is of the type designed to suppress all frequencies below the essential speech range, it follows that the wave filter will also suppress the telephone ringing currents, which are generally of 135 cycles. One way in which the ringing currents may be impressed upon the repeater elements without destroying the efficiency of the wave filter to suppress telegraph signals, is to employ a transformer 50 having a primary winding in circuit with the primary windings of transformers 26 and 27 while the secondary winding is connected in series with the secondary windings of transformers 28 and 29. The primary winding of transformer 50 should preferably be shunted by a condenser 51 of such a value as in combination with the inductance of the primary winding to comprise an anti-resonant circuit for the frequency of the ringing currents, 135 cycles for example. With such an arrangement, transformer 50 will therefore be highly efficient for the transmission of the ringing currents. The value of condenser 51, however, will be such as to substantially short-circuit the primary winding of transformer 50 for the speech currents.

It should also be noted that the trans-

former 50 serves as a by-pass for the ringing currents not only around the filter but also around the potentiometer 25 and the attenuation equalizer, both of the latter elements transmitting ringing currents in- 70 efficiently.

The arrangement described above is intended merely as representative of the preferred embodiment of the invention and it is obvious that many other arrangements 75 are possible and will occur to those skilled in the art.

What is claimed is:

1. In combination, a transmission line, an amplifying repeater, adjustable means between said line and said repeater for attenuating currents of a certain frequency range impressed on said repeater from said line, and a by-pass around said means for impressing other currents directly on said repeater without undergoing attenuation by said means. 80

2. In combination, a transmission line, an amplifying repeater, an electric wave filter between said line and said repeater for freely passing a band of frequencies while suppressing frequencies outside of said band, and a by-pass around said filter for impressing directly upon said repeater currents of a frequency normally suppressed by said filter. 90

3. In combination, an incoming line, an outgoing line, a wave filter therebetween, a transformer having its primary winding connected directly in said incoming line and its secondary winding connected directly in said outgoing line, and a condenser in shunt to one of said windings of such a value that combined with said winding an anti-resonant circuit is produced for a frequency to be transmitted around said filter and through said transformer. 100

4. In combination, a line, a repeater therefor, a wave filter between said line and said repeater, a transformer for coupling said line to said filter, a second transformer for coupling said filter to said repeater, and a third transformer having a winding connected in circuit with a winding of said first transformer and having a second winding in circuit with a winding of said second transformer. 110

5. In combination, a transmission line, a vacuum tube repeater therein, a normally established connection from said line to said repeater including a wave filter for selectively transmitting currents in said line to said repeater, a normally established connection from said line to said repeater around said wave filter for by-passing certain frequencies around said filter and for impressing them directly upon said repeater and a by-pass for currents of other frequencies around said filter and said repeater. 120

6. In combination, a wave filter, and a 130

- path shunted around said filter comprising an anti-resonant circuit for by-passing currents of a certain frequency around said filter.
- 5 7. In combination, a composite telephone and telegraph line, an amplifying repeater in said line, a wave filter for suppressing the telegraph currents and the ringing currents in said line, a by-path around said filter and said repeater for selectively transmitting the telegraph currents, and a by-path around said filter for selectively transmitting directly to the input of said repeater the ringing currents employed in signaling over said line.
- 10 8. A combined telephone and telegraph system, comprising an incoming line, an outgoing line, a vacuum tube repeater there-between, a wave filter in between said incoming line and said repeater, a by-path
- 15 around said filter and said repeater for the telegraph currents in said incoming line, said path comprising an inductance of such a value as to prevent the transmission of speech currents through said path, a transformer for directly coupling said incoming line to said repeater independently of said wave filter, said transformer having one of its windings shunted by a condenser of such a value that combined with said winding an anti-resonant circuit is formed for insuring that said transformer will transmit from said incoming line to said repeater currents of only the ringing frequencies found in said incoming line.
- 20 In witness whereof, I hereunto subscribe my name this 29th day of June A. D., 1921.

RAY S. WILBUR.
